 tion of California

Application August 15, 1949, Serial No. 110,262

23 Claims. (Cl. 84—317)

1

The present invention relates to musical instruments, and more particularly to musical instruments, such as guitars, banjos, and violins, having one or more tensioned strings adapted to be vibrated.

Devices are known for determining the free vibrating length of the string of a musical instrument, through sliding a fret or its equivalent along the string. An object of this invention is to avoid the necessity for sliding the fret along the string by providing for its rolling movement and bodily shifting along the string.

A further object of the invention is to provide an apparatus for bodily rolling an element along a string to vary the free vibrating length of the latter.

Another object of the invention is to provide an improved apparatus capable of varying the pitch in musical instruments by shifting a plurality of inclined plane devices with respect to each other.

Yet another object of the invention is to provide an improved apparatus for conveying an object between different locations.

A further object of the invention is to provide a device for conveying or displacing a movable fret along a tensioned string, with assurance that the fret will maintain its proper relationship to the string during such movement.

Another object of the invention is to provide a device for translating a fret bodily along a tensioned string, in which the fret may be made with a minimum of weight, thereby facilitating movement of the fret by decreasing inertia forces acting upon it.

Still a further object of the invention is to provide a device for moving a fret bodily along a tensioned string, in which the device provides a solid backing or support for the fret against the string, thereby enhancing the duration of the tone emanating from the string.

Another object of the invention is to create a color light effect in a musical instrument that is harmonious with the pitch tones being produced. The color effect can also be provided without any musical tone.

This invention possesses many other advantages, and has other objects which may be made more clearly apparent from a consideration of several forms in which it may be embodied. Such forms are shown in the drawings accompanying and forming part of the present specification. These forms will now be described in detail, illustrating the general principles of the invention; but it is to be understood that such detailed

2

description is not to be taken in a limiting sense, since the scope of the invention is best defined by the appended claims.

Referring to the drawings:

Fig. 12 is a longitudinal section through still another embodiment of the invention;

35 Fig. 13 is a cross-section taken along the line 13—13 on Fig. 12;

Fig. 14 is an isometric projection of still another form of the invention.

In its general aspects, the invention contemplates the movement of a rollable element along and in contact with a tensioned string, to determine the free vibrating length of the latter and the resultant pitch thereof. The rolling element rolls along and in contact with the string, being bodily translated from one position to another by guiding devices that form inclined surfaces or planes. Usually, such inclined surfaces are arranged helically, and are provided on rotatable members that serve to feed the rolling element lengthwise of the tensioned string and in proper engagement therewith.

In the form of the invention illustrated in Figs. 1 to 7, inclusive, the musical instrument includes a body member 10, made of wood or other suitable material, having a string anchoring end 55 or board 11 at one end, and an inclined peg board

12 at the other end. Arranged transversely across the upper surface of the body member is a bridge 13 having spaced notches 14 for the reception of the tensioned strings 15 that are to be placed selectively in vibration. The strings pass through these notches 14 and through other notches 16 at the rear of the bridge, to a position therebelow, where a roller or ball 17 is secured to each string, and engages the lower portions of the bridge 13 on opposite sides of the notches 16, to 10 anchor the ends of the strings 15.

From the anchor end of the instrument, the strings are disposed lengthwise along the upper portion of the body member 10 toward the inclined peg board 12. The strings pass through notches 18 in another bridge 19 on the peg board 12, being secured to the usual tuning posts 20 in the peg board, which may be rotated, in a known manner, by the pegs 21. Tightening of the pegs 21 will serve to stretch the strings 15 between the bridge members 13, 19 and determine the initial tension of the strings, which may be tuned to the desired frequencies.

The strings 15 may be set in vibration, as by plucking by the fingers, the vibrations being transmitted to an electrical pick-up 22 disposed in the anchor end 11 of the body member, for transmission to the desired point. A cover 23 is disposed above and over the anchor end of the strings, and also above the electrical pick-up 22, there being a tone control knob 24 extending through the cover for emphasizing certain frequencies transmitted to the electrical pick-up device.

Four sets of strings 15 are disclosed in the drawings. One or more sets can be employed, and each set may include one or more strings. Inasmuch as the mechanism for determining the free vibrating length of the strings in each set is essentially the same, a detailed description of the operating mechanism for one set of strings will suffice for all.

The free vibrating length of each string 15 is determined by shifting a roller assembly 25 lengthwise along the string, the roller axis being transverse, and preferably at right angles, to the direction in which the strings extend. Each roller assembly includes an intermediate string roller 26 rotatable on a shaft 27 that is fixed to guide rollers 28 on opposite ends thereof. Each guide roller 28 has a flange 29 for precluding substantial endwise movement of the roller assembly along its axis. The string roller is disposed under a set of strings 15, and engages all strings in such set, exerting an upward force thereon. The guide rollers 28 engage inclined guiding surfaces 30 that are disposed under the strings. These surfaces are preferably formed in helical fashion, and serve to feed each roller assembly 25 back and forth along the strings 15.

The helical guide mechanism 31, embodying the surfaces 30, is disposed in a recess 32 in the body member 19 and extends between the anchor end 11 and peg board end 12 of the latter. A shaft or spindle 33 is fixed to the body member, as by being welded, or otherwise secured, to a metallic plate 34 extending transversely across the body member 10 and secured to the latter. A transverse outer bar 35 is rotatably mounted on the spindle 33, as well as a transverse inner bar 36. The ends of the outer bar are secured to two helical guides 37 wound in the same direction, and having the same pitch or lead. The guide surfaces 30 of these helical members, which may

be made of strong, stiff wire, are substantially 180 degrees out of phase. In a similar manner, the ends or outer portion of the inner bar 36 are secured to inner helical guides 38 that are wound in the opposite direction from the outer guides 37, and have substantially the same pitch or lead. The guiding surfaces 30 on the inner members 38 which contact the guide rollers 28 of each roller assembly are also substantially 180 degrees out of phase.

The outer helical guide members 37 extend toward the inclined peg board 12, where they are secured to the outer ends of an outer bar 39 fixed to an outer or tubular shaft 40. Similarly, the inner guide members 38 are secured to the outer ends of an inner bar 41 fixed to an inner shaft 42 extending completely through the outer shaft 40, and also through a plate 43, to a location within the inclined peg board 12. The end of this shaft 42 is attached to the supporting member 43 for the shaft.

The inner helical guide members 38 are wound with an opposite hand from the outer guide members 37. That is, one of the guide members 28 may be equivalent to a steeply pitched, left-hand helical thread, whereas the other guide member is equivalent to a steeply pitched, right-hand helical thread. These guide members engage the guide roller portions 28 of the roller assembly and cradle the roller therebetween. As an example, the guide roller 28 on one end of the roller shaft 27 will engage the outer helical guide 37 at one side of a vertical plane through its axis, and also the inner helical guide 38 on another side of such plane, providing a spaced two-point support for the roller 28. In like manner, the guide roller 28 on the other end of the roller shaft will engage an outer guide 37 and an inner guide 38 on opposite sides of a central vertical plane through the roller axis. In effect, the roller is cradled by the guides, being held firmly by the tensioned strings 15 in engagement with the helical guide surfaces 30, whereas the latter reactively hold the string roller portion 26 in firm engagement with the strings.

The roller assembly 25 is moved along the strings by rotating the inner and outer guides 38, 37 in opposite directions and by the same angular extents. These guides are coaxial of one another, inasmuch as the axis of the fixed spindle 33 is coaxial with the axis of the inner shaft 42. They may be rotated equiangular amounts in opposite directions in various ways. As disclosed in the drawings, a pinion 46 is fixed to the inner shaft 42, which is attached to the inner bar 41, whereas another pinion 47 is fixed to the outer shaft 40 secured to the outer bar 39. These pinions 46, 47 are of the same diameter, and are mounted adjacent one another. One pinion 46 meshes with a lower rack 48 secured to a key 49 slidably mounted in the body member 10 transversely of the shafts 40, 42 whereas the other pinion 47 meshes with an upper rack 50 suitably secured to the same key 49. It is apparent that movement of the key 49 by the person's finger will move the racks 48, 50 longitudinally, but since they are engaging the pinions 46, 47 on opposite sides of the common axis of the latter, the pinions will be rotated in opposite directions, to correspondingly rotate the inner and outer helical guides 38, 37 in opposite directions.

Inward movement of the key 49 by the person's fingers is resisted by the helical spring 44, so that removal of such force causes the energy stored in the spring to rotate the pinion 46 fixed to the

shaft 42 in a reverse direction, which correspondingly shifts the key 49 in the reverse direction, and also the pinion 47 attached to the outer shaft 40 in the reverse direction.

It is, accordingly, apparent from the foregoing description that longitudinal movement of a key 49 will rotate the helical guides 37, 38 in opposite directions. As the guides are rotated, they will shift the cradle roller assembly 25 longitudinally of the strings 15. The guide rollers 28 at all times have a four-point contact with the helical guides, which positively convey it along the strings, and also hold it in proper assembled relation with respect to the strings. Inasmuch as the string roller portion 26 of the assembly is rotatable on the shaft 27, movement of the assembly along the strings can occur, with the string roller portion rolling under the strings 15 without any sliding friction, thus insuring a smooth operation to the device, with a minimum of extraneous noise. The guide roller flanges 29 prevent substantial endwise movement of the roller assembly 25 by engaging the outer guides 37.

A plurality of sets of strings 15 and roller assemblies 25, and associated mechanism, is disclosed. Each set has its rack and pinion and return spring arrangement, which is the same as the arrangement shown most clearly in Fig. 3. Of course, the racks 48, 50 on the keys 49 are so located and arranged thereon as to engage with only a single set of pinions 46, 47, each key being effective for accomplishing bodily translation of only a single roller assembly 25 along a set of strings.

Four keys are disclosed in the form of the invention shown in Figs. 1 to 7, inclusive, so as to enable the four fingers of the left hand to selectively manipulate the keys 49. If desired, one or more of the keys may be manipulated by a person's foot. For that reason, a pedal operated device is shown in Figs. 3 and 7, one device for each key to which it is applied, as the outermost two keys. Each pedal operated device includes a pedal 55 pivoted to a suitable support or base 56. The outer end of the pedal is pivotally connected to a link 57, extending upwardly toward the instrument, the other end of the link being pivoted to an operating lever 58 mounted on a pin 59 carried by the instrument body 10. The opposite end of the operating lever supports a roller 60 engaging the end of the key 49.

Depression of the pedal 55 will rock the operating lever 58 in counter-clockwise direction, as seen in Fig. 7, to shift the key 49 inwardly and bodily translate the roller assembly 25 along the strings 15. Return movement of the pedal 55 is accomplished by the helical spring 44 disposed around the shaft. The force of such spring may be supplemented by disposing another coil spring 61 between the pedal 55 and the supporting base 56, which will tend to elevate the pedal device and remove the inwardly directed force from the key 49.

By appropriate manipulation of the keys 49, each roller assembly 25 may be bodily translated along the length of the one or more strings 15 in each set, and the string appropriately placed in vibration, as by plucking, to produce the desired fundamental notes. The sounds are picked up by the electromagnetic device 22 for transmission to a speaker (not shown).

In the form of invention disclosed in Figs. 8 to 11, inclusive, the helical guiding surfaces 30a are formed on tubular members 62, 63. A cylindri-

cal tube is cut along two helical lines to provide guiding surfaces 30a displaced substantially 180 degrees from one another in phase. The inner and outer helically cut tubular guides 63, 62 are made in this manner, the inner guide 63 being disposed within the outer guide 62. The outer guide 62 has an end plate 64 welded, or otherwise suitably secured, to it, which is rotatable upon a fixed spindle 33a at the anchor end of the instrument, the other end of the guide 62 being secured to an end plate or filler member 65 attached to the outer shaft 40a. The inner helical guide 63 has end plates 66, 67 secured to it, one end plate 66 being rotatable on the fixed spindle 33a, and the other end plate 67 being secured to the shaft 42a extending through the outer shaft 40a, in substantially the same manner as in the other form of the invention.

The helical guiding surfaces 30a on the inner and outer tubular members 63, 62 are relatively disposed in essentially the same manner as in the other form of the invention. The guide rollers 28 of each roller assembly is nested at all times in a concavity 68 formed between the helical guides 62, 63. As before, the helical surfaces 30a on the inner guide 63 are of the opposite hand from the opposite surfaces 30a on the outer guide 62, the guide rollers being cradled in the concavity which these guide surfaces form, as disclosed in Fig. 9, in which a four-point contact is provided between the guide rollers 28 and the helical guiding surfaces on the inner and outer tubular members. The same rack and pinion arrangement as in the other form of the invention may be employed for shifting the roller assembly 25 along the strings. In all respects, the operation of the instrument shown in Figs. 8 and 9 is the same as that illustrated in Figs. 1 to 7, inclusive. The advantage of the arrangement shown in Figs. 8 and 9 is that it is more rigid, and may be made with a greater degree of accuracy and assurance of an extended life.

As disclosed in Figs. 8 to 11, inclusive, the tubular members 62, 63 cooperate with one another to form an enclosure except in certain regions, as the particular point at which the roller assembly 25 is located at the time. This enclosure arrangement is availed of to enable color effects to be provided. To accomplish this objective, a fluorescent light tube 70, or other source of illumination, is disposed within the lower portion of the tubular members 62, 63 and extends lengthwise thereof, the tube being supported in end brackets 71, 72. One of the brackets 72 may be fixedly secured in the fixed spindle 33a, whereas the other bracket 71 may have an extension 73, piloted within the rotatable shaft 42a, so as not to rotate with the latter. Disposed above the fluorescent light tube 70 is a transparent or semi-transparent strip 74, which may possess different colors along its length, these colors being chosen as to correspond with the position of the roller assembly 25 along the strip, and, consequently, with the frequency of vibration emanating from the strings 15. The fluorescent tube 70 itself could be provided with different colors along its length, rather than the transparent or semi-transparent strip 74. Current is fed to the tube 70 through suitable leads 75, 76, the leads running through and out of the stationary spindle 33a.

As the instrument is being played, the roller 25 is shifted along the strings 15. At the location of the roller 25, the inner and outer tubes 63, 62 are arranged with respect to each other as to

provide an opening 77 through which light from the tube 70 can shine upwardly. At other portions along the helical tubular guides, the light is presented from showing upwardly. Accordingly, a color light effect can be caused to shine through the instrument that is harmonious with the pitch tones being produced. For that matter, the color effect can be provided merely by rotating the inner and outer tubular guides 63, 62 in opposite directions, without setting the strings 15 into vibration, thereby merely producing color harmony without any musical tones.

In the form of invention disclosed in Figs. 12 and 13, a single helical guide 80 is provided for shifting the roller assembly 25a lengthwise along the strings. Since only a single helical guide is furnished, it is only necessary to provide a single rack and pinion arrangement for rotating the guide. Thus, a rack 81 is secured to a key 82 meshing with a pinion 83 that is fixed to a shaft 84 attached to the helical guide 80. The other end of the helical member is secured to a spindle 85 rotatable in a bracket 86 attached to the frame 87 of the instrument. The opposite surfaces or edges 88 on the helical guide 80 are substantially 180 degrees from each other, and are arranged to contact the guide roller portions 28a of the roller assembly holding the string roller portion 26a in engagement with the tensioned strings 15 thereabove. These latter strings also hold the roller assembly 25a downwardly against the helical guide 80 as well as a toothed pinion 89, formed on each roller guide member 28a, in proper engagement with a stationary rack 90 arranged lengthwise of and adjacent the helical guide. Actually, there is a rack 90 for each pinion 89, and these racks are disposed on opposite sides of the helical guide member 80 and extend substantially along its entire length.

As the helical guide 80 is rotated about its axis in either direction, through appropriate manipulation of the key 82, rack 81, and pinion 83, the helical surfaces 88 on the guide shift the roller 25a along its racks 90 and along the strings 15. The meshing of the guide roller pinions 89 with the guide racks 90 insures proper traverse of the roller assembly along the strings 15 and its appropriate alignment with all of the operating parts.

In the form of invention disclosed in Fig. 14, the roller assembly 25b may be shifted along the strings 15 by bodily translating a plurality of oppositely inclined plane devices. The roller assembly 25b is essentially the same as was described in connection with the other forms of the invention. Its stringed roller portion 26b is in contact with one or more tensioned strings 15, whereas the lower surfaces of the guide roller portions 28b are in engagement with straight guide bars 95, 96. A pair of parallel guide bars 96 is arranged on opposite sides of the strings 15, and are inclined in one direction. Another pair of parallel guide bars 95 is disposed on opposite sides of the strings within the first-mentioned guide bars 96, and are inclined in the opposite direction. The guide rollers 28b at one side of a roller assembly 25b engages an outer straight guide bar 96 and also an inner straight guide bar 95, which is also true of a guide roller 28b at the other end of the assembly 25b, which is in simultaneous engagement with an inner guide bar 95 and an outer guide bar 96 on the other side of the strings 15. In effect, the roller assembly 25b is cradled between the guide bars 95, 96, in essentially the same manner as the helical guide surfaces in the

other forms of the invention cradle their guide rollers.

As disclosed in Fig. 14, the roller assembly 25b may be bodily translated lengthwise of the strings 15 by moving the guide bars 95, 96 vertically, the outer inclined guide bars 96 being shifted in the opposite direction from the inner guide bars 95. To accomplish such movement, the ends of the outer guide bars 96, at one end of the instrument, are secured to the upper portions of outer vertical rack members 97, which are attached together as by use of a cross-piece 98, the other ends of the same guide bars 96 are secured to the lower ends of corresponding rack members 97a. The rack members 97, 97a occupy substantially the same elevation, inclining the guide bars 96 because the attachment of the latter to the upper and lower portions of the rack members.

The inner guide bars 95 at one end thereof are secured to the lower portions of the inner racks 99, whereas the other ends of the inclined inner bars are secured to the upper portions of another pair of inner racks 99a. The opposite inclined guide bars 95, 96 are disposed closely adjacent one another, a pair of bars 95, 96 engaging the guide roller portion 28b of the guide roller assembly at each side of the string. However, the guide bars 95, 96 are laterally displaced from one another, so as to permit extension of shafts 100 from the sets of racks 97a, 99a at the other end of the instrument.

The outer guide bars 96 are secured to internally toothed racks 97, 97a; whereas the inner guide bars 95 are attached to externally toothed racks 99, 99a. This toothed arrangement is provided so as to enable the racks to engage pinions 101 that are mounted on a pair of shafts 100 extending along the instrument. Thus, a pair of pinions 101, 102 is provided at each end of the instrument, a pinion 101 or 102 at one end being secured to the same shaft 100 as the pinion 101 or 102 at the other end, so as to move jointly.

One of the inner racks 99 may be provided with a suitable key 103 for manipulation by the person's finger. Depression of the rack 99 will shift the inner inclined guide bars 95 downwardly, and because of meshing of these racks with the pinions 101, 102, will cause the outer guide bars 96 to be elevated, or moved in the opposite direction. The opposite inclination of these bars 96, 95 will cause them to shift the roller assembly 25b lengthwise of the string, and thereby determine the free vibrating length thereof. Of course, movement of the racks 99 in the opposite direction will correspondingly shift the roller assembly in the opposite direction.

It is, accordingly, apparent that the free vibrating length of the string of musical instruments can be determined by rolling a member, such as a movable fret, bodily along a tensioned string. Such movement is positive in character, since the upper portion of the movable fret is in engagement with the string or strings 15, and the lower portion with the inclined guiding members. Since the fret is held positively between the strings and the guiding members, it may be made to possess a minimum of weight, since its weight is not a factor in moving it bodily along the tensioned string. For that reason, movement of the fret is facilitated because of its light weight and the accompanying decrease in the inertia forces acting upon it.

The movable fret or rolling element will always maintain its proper relationship to the string during its movement, because it is positively shifted

in both directions by the inclined surfaces on the guides. Moreover, these guides provide a solid backing for the fret against the string, serving the purpose of enhancing the duration of the tone emanating from the string. This is especially true of the tubular guide arrangement illustrated in Figs. 8 and 9, which is extremely rigid.

Where color harmony is desired, the shiftable opening of the tubular guide members, accompanied by the variations in the color of the tube along the string, provides very pleasing color effects.

The inventor claims:

1. In a musical instrument: a tensioned string; a rollable member having a surface in contact with said string; and means providing one or more inclined guiding surfaces in engagement with said surface of said rollable member for bodily translating said rollable member along said string.

2. In a musical instrument: a tensioned string; a fret member in contact with said string; a rotatable member disposed lengthwise of said string; said rotatable member having an inclined guiding surface thereon engaging said fret member to bodily translate said fret member along the string upon rotation of said rotatable member.

3. In a musical instrument: a tensioned string; a roller member in contact with said string; a rotatable member disposed lengthwise of said string; said rotatable member having a helical guiding surface thereon engaging said roller member to bodily translate said roller member along the string upon rotation of said rotatable member.

4. In a musical instrument: a tensioned string; a roller member in contact with said string; a rotatable member disposed lengthwise of said string; said rotatable member having a helical guiding surface thereon engaging said roller member to bodily translate said roller member along the string upon rotation of said rotatable member; said roller member comprising a string engaging portion and a portion engaging said guiding surface and rotatable with respect to said string engaging portion.

5. In a musical instrument: a tensioned string; a fret member in contact with said string; means providing a plurality of guiding surfaces inclined in opposite directions and simultaneously engaging said fret member; and means for moving said guiding surfaces simultaneously in opposite directions to translate said fret member bodily along said string.

6. In a musical instrument: a tensioned string; a roller member in contact with said string; a first rotatable member disposed lengthwise of said string; a second rotatable member disposed lengthwise of said string and located within said first member; said rotatable members having helical guiding surfaces thereon engaging said roller member, the helical surface of said first member being of the opposite hand from the helical surface of said second member; and means for rotating said rotatable members simultaneously in opposite directions to translate said roller member bodily along said string.

7. In a musical instrument: a tensioned string; a roller member in contact with said string; a first rotatable member disposed lengthwise of said string; a second rotatable member disposed lengthwise of said string and located within said first member; said rotatable members having helical guiding surfaces thereon engaging said

roller member, the helical surface of said first member being of the opposite hand from the helical surface of said second member; and means for rotating said rotatable members simultaneously in opposite directions to translate said roller member bodily along said string; said roller member comprising a central string engaging portion and portions on opposite sides of said central portion engaging said guiding surfaces and rotatable with respect to said central portion.

8. In a musical instrument: a tensioned string; a roller member in contact with said string; a first rotatable member disposed lengthwise of said string and having a pair of helical guiding

15 surfaces displaced substantially 180 degrees from each other and engageable with said roller member; a second rotatable member disposed lengthwise of said string and located within said first rotatable member, said second rotatable member

20 having a pair of helical guiding surfaces displaced substantially 180 degrees from each other and engageable with said roller member; the helical surfaces of said first member being of the opposite hand from the helical surfaces of said

25 second member; and means for rotating said rotatable members simultaneously in opposite directions to translate said roller member bodily along said string.

9. In apparatus of the character described: a 30 movable member; a first rotatable member; a second rotatable member located within said first member; said rotatable members having helical guiding surfaces thereon engaging said movable member, the helical surface of said first mem-

35 ber being of the opposite hand from the helical surface of said second member; and means for rotating said rotatable members simultaneously in opposite directions to translate said movable member bodily along said rotatable members.

10. In apparatus of the character described: a first rotatable member; a second rotatable member located within said first member; said rotatable members having helical surfaces thereon, the helical surface of said first member being of the opposite hand from the

45 helical surface of said second member; and means for rotating said rotatable members simultaneously in opposite directions.

11. In apparatus of the character described: a 50 first rotatable member; a second rotatable member located within said first member; said rotatable members having helically arranged side surfaces thereon, the helical surface of said first member being of the opposite hand from the

55 helical surface of said second member; means for rotating said rotatable members simultaneously in opposite directions; a source of illumination within said rotatable members for translating light through one or more open portions defined

60 by the helical surfaces of said members.

12. In a musical instrument: a tensioned string; a roller member in contact with said string; a first rotatable member disposed lengthwise of said string; a second rotatable member

65 disposed lengthwise of said string and located within said first member; said rotatable members having helical guiding surfaces thereon engag-

70 ing said roller member, the helical surface of said first member being of the opposite hand from the helical surface of said second member;

75 and means for rotating said rotatable members simultaneously in opposite directions to translate said roller member bodily along said string; a source of illumination within said rotatable members for transmitting light through an open

portion defined by the helical guiding surfaces of said rotatable members, such open portion being located at the position occupied by said roller member along the string.

13. In a musical instrument: a tensioned string; a roller member in contact with the string; a rotatable member disposed lengthwise of the string and having a helical surface engaging said roller member; and a rack in engagement with said roller member.

14. In a musical instrument: a tensioned string; a roller member in contact with the string; a rotatable member disposed lengthwise of the string and having a helical surface engaging said roller member; and stationary racks on opposite sides of said rotatable member and in engagement with said roller member.

15. In a musical instrument: a tensioned string; a roller member in contact with said string; a first rotatable member disposed lengthwise of said string; a second rotatable member disposed lengthwise of said string; said rotatable members having helical guiding surfaces thereon engaging said roller member, the helical surface of said first member being of the opposite hand from the helical surface of said second member; and means for rotating said rotatable members simultaneously in opposite directions to translate said roller member bodily along said string.

16. In a musical instrument: a tensioned string; a fret member disposed below and in contact with said string; means below said fret member providing a plurality of guiding surfaces inclined in opposite directions and simultaneously engaging said fret member to force said fret member against said string; and means for moving said guiding surfaces simultaneously in opposite directions to translate said fret member bodily along said string.

17. In a musical instrument: a tensioned string; a roller member disposed below and in contact with said string; a first rotatable member disposed lengthwise of said string and below said roller member; a second rotatable member disposed lengthwise of said string and located within said first member; said rotatable members having helical guiding surfaces thereon engaging said roller member to urge said roller member upwardly against said tensioned string, the helical surface of said first member being of the opposite hand from the helical surface of said second member; and means for rotating said rotatable members simultaneously in opposite directions to translate said roller member bodily along said string.

18. In apparatus of the character described: a movable member; a first rotatable member; a second rotatable member located within said first member; said rotatable members each having a pair of helical guiding surfaces thereon displaced substantially 180 degrees from each other, and engageable with said movable member, said helical surfaces of said first rotatable member being of the opposite hand from the helical surfaces of said second member; and means for rotating said rotatable members simultaneously in opposite directions to translate said movable member bodily along said rotatable members.

19. In apparatus of the character described: a movable member; a first rotatable member of fragmentary tubular form; a second rotatable member of fragmentary tubular form, said second rotatable member being disposed within said first rotatable member; said rotatable members

each having a pair of helical guiding surfaces thereon extending longitudinally thereof and engageable with said movable member; and means for rotating said rotatable members simultaneously in opposite directions to translate said movable member bodily along said rotatable members.

20. In apparatus of the character described: a movable member; a first rotatable member of fragmentary tubular form; a second rotatable member of fragmentary tubular form, said second rotatable member being disposed within said first rotatable member; said rotatable members each having a pair of helical guiding surfaces thereon extending longitudinally thereof and engageable with said movable member; means for rotating said rotatable members simultaneously in opposite directions to translate said movable member bodily along said rotatable members; and a source of illumination within said rotatable members for transmitting light through an open portion defined by the helical guiding surfaces of said fragmentary tubular rotatable members, such open portion being located at the position at which said movable member is in engagement with said rotatable members.

21. In apparatus of the character described: a rollable member; a first rotatable member; a second rotatable member located within said first member; said rotatable members having helical guiding surfaces thereon engaging said rollable member on one side of a plane through the axis of said rollable member, said plane being parallel to the axis of said rotatable members; the helical surface of said first member being of the opposite hand from the helical surface of said second member; and means for rotating said rotatable members simultaneously in opposite directions to translate said rollable member bodily along said rotatable members.

22. In a device of the character described: a first member providing a pair of spaced substantially parallel guiding surfaces; a second member providing a pair of spaced parallel guiding surfaces, the plane of said guiding surfaces of said second member intersecting the plane of said guiding surfaces of said first member; a movable element extending transversely of said members above the line of intersection of the planes of said guiding surfaces, said movable element contacting the guiding surfaces of said first member on one side of said line of intersection, and contacting the guiding surfaces of said second member on the other side of said line of intersection; and means for relatively moving said members to translate the line of intersection of said planes of said guiding surfaces to translate said movable element supported thereabove.

23. In a device of the character described: a first member providing a pair of spaced substantially parallel guiding surfaces; a second member providing a pair of spaced parallel guiding surfaces, the plane of said guiding surfaces of said second member intersecting the plane of said guiding surfaces of said first member at an angle; a movable element extending transversely of said members and supported by said surfaces of said members above the line of intersection of the planes of said guiding surfaces, said movable element contacting the guiding surfaces of said first member on one side of said line of intersection, and contacting the guiding surfaces of said second member on the other side of said line of intersection; and means for relatively moving said members to translate the line of in-

13

tersection of said planes of said guiding surfaces in a direction inclined with respect to said planes and at substantially half the said angle of intersection thereof to translate said movable element supported thereabove.

JOHN W. McBRIDE.
